CLAIM

The ornamental design for a garment rack as shown and described.

DESCRIPTION

FIG. 1 is a front left side perspective view showing the new design for a garment rack;

FIG. 2 is a rear right side perspective view thereof;

FIG. 3 is a front view thereof;

FIG. 4 is a left side view thereof;

FIG. 5 is a rear view thereof;

FIG. 6 is a right side view thereof;

FIG. 7 is a bottom plan view thereof;

FIG. 8 is a top plan view thereof;

FIG. 9 is a front left side perspective view showing the new design for a garment rack in accordance with another embodiment;

FIG. 10 is a rear right side perspective view thereof;

FIG. 11 is a front view thereof;

FIG. 12 is a left side view thereof;

FIG. 13 is a rear view thereof;

FIG. 14 is a right side view thereof;

FIG. 15 is a bottom plan view thereof; and,

FIG. 16 is a top plan view thereof.

The broken lines shown illustrate portions that form no part of the claimed design.
